UNITED STATES PATENT OFFICE.

JACOB HUNZINGER, OF BROOKLYN, NEW YORK.

WOOD-CARVING MACHINE.

SPECIFICATION forming part of Letters Patent No. 463,836, dated November 24, 1891.

Application filed April 13, 1891. Serial No. 388,627. (No model.)

To all whom it may concern:

Be it known that I, JACOB HUNZINGER, of Brooklyn, Kings county, State of New York, a citizen of Switzerland, have invented certain new and useful Improvements in Wood-Carving Machines, of which the following is a specification.

This invention relates to an improved wood-carving machine of that class in which the wood to be operated upon is supported on an adjustable table and in which the carving-tools are supported in bearings at the outer ends of jointed frames that are hinged to a vertically-supported transmitting-shaft and provided with a guide-pin vertically above the spindle of the carving-tool, the pin being supported in horizontal arms of the jointed frame, so as to be guided along the pattern which is supported on the top part of the machine.

The invention consists, in its general features, of a wood-carving machine in which the supporting-table for the wood to be carved is adapted to be adjusted vertically, as well as into a forwardly or backwardly inclined position; secondly, of a stop-motion for interrupting the rotary motion of the carving-tool by shifting its transmitting-belt to a loose pulley, and, thirdly, in a device for adjusting the spindle of the carving-tool, as well as the spindle of the guide-pin, into laterally-inclined position, so as to extend thereby the range of the work which can be performed by the carving-machine.

The invention consists, further, of certain additional details of construction, which will be fully described hereinafter, and finally pointed out in the claims.

In the accompanying drawings, Figure 1 represents a side elevation of my improved carving-machine. Fig. 1^a is a detail sectional view of one of the sleeves on the spindle and pulleys thereon. Fig. 1^b is a sectional plan view on the line x x, Fig. 1^a. Fig. 2 is a plan of the same. Fig. 3 is a front elevation of the same. Figs. 4 and 5 are details of the adjusting mechanism for the spindle of the carving-tool. Figs. 6, 7, and 8 are details of the adjusting mechanism of the spindle of the guide-pin, and Fig 9 is a detail section of the stop-motion by which the rotary motion of the carving-tool can be stopped.

Similar letters of reference indicate corresponding parts.

In the drawings, A represents the supporting-frame of the table B of my improved carving-machine, which frame consists of two upright main standards a, which are connected by a top shelf a', on which the patterns are supported that are to be reproduced, while the lower part of the frame is connected by cross-pieces a². The table B is provided with transverse bottom brackets a³, mounted to turn on a shaft a⁸, held in vertically-adjustable bearings a⁹, as shown in Fig. 3, which bearings are guided in vertical slots of the upright standards a⁵ and adjusted by means of vertical screw-spindles a⁴, which engage interiorly-threaded sleeves of said bearings a⁹. The lower ends of the vertical screw-spindles a⁴ are provided with bevel-wheels which mesh with the bevel-wheels of a longitudinal shaft a⁶, that is provided with a hand-wheel at one end, so that on turning said hand-wheel in one or the opposite direction the screw-spindles are turned in one or the opposite direction, and thereby the guide-bearings of the table B raised or lowered, according to the position to which the table is to be adjusted. To the under side of the table B is applied at one end a fixed toothed segment b, which meshes with a pinion b', the shaft of which is supported in one bearing a⁹, which pinion is provided with a hand-wheel b², by which rotary motion may be imparted to the pinion, so that the table B may be adjusted to a forward or backward inclination, as required by the work to be done. When the table is adjusted, it is retained rigidly in position by means of pivot-straps d, that are attached to both ends of the table, and clamped by means of clamping-nuts d' in vertical slots in the main standards a, as shown in Fig. 1. These straps remove the strain from the toothed segment and secure the rigid position of the supporting-table B. The table B is provided with a number of short slots d², as shown in Fig. 2, so as to permit the convenient clamping, by means of suitable devices A', of the different sizes of wooden blanks to be operated upon. The top shelf a' is likewise slotted, so as to secure the patterns in the same manner.

The carving operation is performed by

means of three carving-tools D, the spindles S of which are supported in suitable bearings at the outer ends of jointed supporting-frames, each of which is formed of two sections D' 5 and D², of which the latter is applied by sleeve-shaped ends to a vertical shaft E, that is supported in suitable bracket-bearings and rotated by a suitable belt-and-pulley transmission. The different supporting-frames D' 10 D² for the carving-tools D are preferably so arranged as to bring the entire length of the supporting-table within easy and convenient reach of the carving-tools. The front section D' of each supporting-frame is connected 15 with the rear section D² by a fixed spindle D³, on which are loosely mounted three splined sleeves T, on which the rear end of the front section D' can slide vertically, as required, when following the motion of the carving- 20 tool from the wooden blanks. Each front section D' is also provided with a forwardly-extending bracket-arm F, formed of a central rod and two curved rods or braces that are united at the front end to form a support for 25 the guide-pin f, which is held vertically above and in line with the spindle of a carving-tool, so that when the guide-pin is moved over the pattern an exact reproduction of the same is produced by the carving-tool on the blank to 30 be carved. To the upper end of the front section D' is connected by a pivot-link d⁴ a weighted arm D⁸, that is fulcrumed to a short standard mounted to turn on the upper part of the rear section D², said weighted arm serving to counterbalance the front section D' and 35 the forwardly-extending bracket-arm of the guide-pin, so that the same follows freely the up-and-down motion of the guide-pin as it passes over the pattern. On the upper end 40 of the lowermost of the spline-sleeves T the two independent pulleys e e' are mounted loosely, and above the same the independent loose pulley e² is mounted. A driving-belt e³ passes around the pulley e' and around a pulley on the shaft E, and a belt f' passes around the pulley e, connected with the pulley e', and also around a pulley e⁴ on the upper end of the carving-tool spindle S. The jointed sections D' and D² can be set at any suitable 45 angle to each other, according to the position required by the carving-tool, while the motion-transmitting pulleys and belts impart the rotary motion to the carving-tool. A handle D⁴ is applied to the front end of the front section 50 D', by means of which the carving-tool may be moved over the material to be carved, while the guide-pin f is guided over the pattern on the top shelf a'.

When it is desired to interrupt the rotary motion of the carving-tool, the transmitting-belt e³ is shifted from the fixed pulley e' on the sleeve T to the loose pulley e² on the same, which is accomplished by a belt-shifting device that is shown in Figs. 1 and 9. It is constructed of a fulcrumed lever g, provided at its lower end with a sleeve g', through which the transmitting-belt e³ passes, and connected

at its upper end by a pivot-link g² with a slide-piece g³, that is guided in a fixed guide-sleeve g⁴ and provided at its under side with a longitudinal recess, in which recess is arranged a fulcrumed and spring-actuated latch g⁵, the outer end of which is engaged by a hook g⁶, attached rigidly to the spindle of an axially-turning button g⁷. The hook engages the upwardly-bent rear end of the latch, while the downwardly-bent front end of the latch abuts against the guide-sleeve g⁴ when the shifting device is not called into action. When it is desired to stop the motion of the 80 carving-tool, the button g⁷ is turned so that its hook g⁶ tilts the fulcrumed latch and permits it to be moved with the slide-piece g³, through the sleeve g⁴, until the end of the latch arrives at the opposite end of the sleeve 85 in the position shown in Fig. 9, in which position it is retained by the abutting of the button against the end of the sleeve. By the oscillating motion imparted to the fulcrumed lever g the motion-transmitting belt e³ is 90 shifted upon the loose pulley by the lifting action of the sleeve g³, and thereby the rotary motion of the carving-tool is interrupted. By returning the latch and slide-pieces into their normal position (shown in Fig. 1) the 95 fulcrumed lever returns the transmitting-belt to the pulley e' and imparts thereby rotary motion to the spindle of the carving-tool. The transmitting-shaft E is also provided with a loose pulley to which the transmitting-belt 100 may be shifted, so that no motion is transmitted from the driving-shaft E to the transmitting-belts.

The spindle of the carving-tool, as well as the spindle of the guide-pin f, is arranged to 105 be adjusted at a suitable inclination from either side to the vertical axis. The adjustment of the spindle of the carving-tool is accomplished by means of a disk m, held on the front end of the section D' and provided with 110 arc-shaped slots m', through which the bolts m² pass, that have their heads held in the box M, in which the spindle of the carving-tool rotates. The inclination that is to be given to the spindle can readily be determined by 115 a scale arranged on the rim of the disk m and a pointer on the casing or box of the tool-spindle. The spindle of the guide-pin f is set to a corresponding degree of inclination by means of the disk N on the front end of 120 the supporting bracket-arm F and a disk N' in which the guide-pin is held. The central part of the guide-pin disk is perforated for a screw-spindle O, on which are arranged the nuts O', that serve to tightly hold the guide-pin disk after it has been adjusted to the proper degree of inclination against the disk N. When the carving-tool is adjusted to any angle of inclination, the guide-pin must be likewise adjusted, so as to reproduce the pattern. 130

When either one of the side tools is not required for use, the frame of the same is moved to the end of the supporting-frame A and is

supported in spring-clasps P, which engage the tool-spindle, one spring-clasp being applied to each end standard and the second spring-clasp to an arm attached to a strap 5 that is guided in keepers of each upright standard a, as shown clearly in Figs. 1 and 2. The straps may be readily adjusted in position to the spindle, so as to retain the same in position of rest when not required for use, as 10 shown at the right-hand side of Fig. 2.

The advantages of my improved carving-machine over similar machines of this class are, first, the facility with which every part 15 of the pattern on the supporting-table can be reached by one or the other of the carving-tools, so that large and small pieces can be carved; secondly, the easy raising and lowering of the carving-tool by the front section of the jointed frame; thirdly, the adjustment of 20 the supporting-table to the work required to be carved; fourthly, the facility with which any one of the carving-tools may be placed out of work by the belt-shifting device; and, lastly, the advantages by which the spindle 25 of the carving-tool, as well as the guide-pin, may be adjusted to an inclined position for accomplishing work that could not so well be performed by a vertical position of the carving-tool and guide-pin.

30 Having thus described my invention, I claim as new and desire to secure by Letters Patent—

1. The combination, with a counterbalanced front section supporting the carving-tool and 35 guide-pin, a rear section supported on an upright driving-shaft, and a spindle for connecting the front and rear sections, and splined sleeves mounted on said spindle to turn on the same and on which sleeves the front section 40 can slide, said sleeves turning with the front section, substantially as set forth.

2. The combination, with a jointed supporting-frame composed of a rear section supported on an upright driving-shaft, a front section, and a spindle for connecting said sections, 45 and splined sleeves mounted to turn on the spindle with the front section, on which sleeves

the front section can slide, of a carving-tool at the front end of the front section, motion-transmitting belts and pulleys for the transmission of rotary motion to the carving-tool, and a belt-shifting device for one belt, whereby the motion of the carving-tool may be interrupted, substantially as set forth. 50

3. In a carving-machine, the combination, 55 with a bracket-arm containing a rotating carving-tool, means for operating said tool, a forwardly-extending bracket-arm, a jointed supporting-frame above the arm carrying the carving-tool, said bracket-arm being provided 60 with a fixed disk, an adjustable disk on said fixed disk, a guide-pin on said adjustable disk, a horizontal screw-spindle at the free end of the bracket-arm, and jam-nuts for adjusting the guide-pin to any suitable inclination on 65 the disk of the bracket-arm, substantially as set forth.

4. In a carving-machine, the combination, 70 with a supporting-frame, of a table, vertically-adjustable bearings with which the table is pivotally connected, gearing and screws for adjusting table vertically, a segmental rack on the under side of the table, gearing engaging said rack and mounted on one of the bearings, and a rotating swinging cutting-tool located above the table, toward and from which cutting-tool said table can be shifted vertically, so as to adapt the tool to cut into the wood placed upon the said table, substantially 75 as set forth. 80

5. In a carving-machine, the combination, 85 with a vertically-adjustable swinging table, of a link pivotally connected with said table and bearings held in the end of said link and passing through a vertical slot in the standard of the table-supporting frame, substantially as set forth.

In testimony that I claim the foregoing as my invention I have signed my name in presence of two subscribing witnesses.

JACOB HUNZINGER.
